GUARD RAIL

Edward Welch, Valley Falls, R. I.

Application June 2, 1950, Serial No. 165,718

8 Claims. (Cl. 256—13.1)

11

My present invention relates to guard rails, and more particularly to a guard rail for sporting events involving animals.

The principal object of the present invention is to provide a guard rail for a race track, polo field, or similar area, which will protect the horses against injury.

A further object of the present invention is to provide a safety guard rail which will prevent horses or other animals from being injured by splinters.

Another object of the present invention is to provide a guard rail which will protect horses or other animals from serious injury.

With the above and other objects and advantageous features in view, my invention consists of a novel arrangement of parts more fully disclosed in the detailed description following, in conjunction with the accompanying drawings and more particularly defined in the appended claims.

In the drawings, Fig. 1 is a perspective view of a section of guard rail embodying my invention.

Fig. 2 is a section thereof taken on line 2-2 on Fig. 1.

Fig. 3 is a longitudinal section of a portion of the guard rail.

Race tracks, polo fields and similar sporting areas involving animals are provided with guard rails defining the track or field. In the case of race tracks, the inner rail is the shortest distance around and race horses are trained to bear inwardly towards the rail. Very often, a horse is bumped into the rail, or bolts into the rail, and serious injury can result to both the horse and the jockey. Many times valuable race horses must be destroyed because of violent contact with the track rail.

Polo fields are provided with a very low wooden rail defining the playing area and occasionally a polo pony will stumble against such a rail and suffer serious injury.

The present invention is designed to provide a guard rail which is rigid enough and firm enough to act as a proper railing for defining the track or polo field area, but which will give and even collapse under the impact of a horse without injuring the animal.

The present invention may be modified to apply to any type of area involving horses or other animals. However, for purposes of illustration, I have shown the present invention as applied to a race track guard rail.

The race track guard rail is usually approximately 30 inches high and the upper surface of the rail must be well defined so that the jockey can readily see the rail. Most jockeys take a quick glance downwardly and it is often difficult for them to properly define the rail on a cloudy or rainy day from their position on a speeding race horse. For this reason, in the present invention the upper surface of the rail has been made wider than the side edge thereof and slightly angularly disposed to give the jockey the most favorable view thereof. Referring to the drawings, I provide a plurality of rail posts 10 of rigid material such as steel or iron tubing, of any desired cross section, but preferably rectangular cross section, as shown in Fig. 4. This will give the posts 10 more rigidity. The posts 10 may be imbedded in concrete or cement 11, as shown in Fig. 2, or, if desired, may be positioned in a removable socket in the concrete for ready replacement. To protect the feet of the horses against contact with the steel or iron posts 10, each post may be covered with a rubber sheathing 12, as shown in Fig. 4. The posts 10 comprise vertical portions 13 and integral loop portions at the upper end of generally rectangular shape. These loop portions comprise an upper downwardly inclined portion 14, a comparatively short vertical portion 15 and terminate in a lower horizontal portion 16 which extends back against the vertical portion 13, as shown in Fig. 2. This provides an extended area laterally of the vertical portion of the post and having a wide upper portion 14 inclined at an angle. The posts 10 may be positioned the conventional eight feet apart along the inner edge of the track, with the upper loop portion extending laterally outwardly toward the track area. In this manner, the horses will always be kept a sufficient distance away from the vertical portion of the posts so as to prevent their legs accidentally kicking the posts. The rail portion comprises a plurality of L-shaped sheets of rubber 17, the long leg 18 extending across the top arms 14 of the posts 10, and the short legs 19 extending vertically outside the short arms 15 of the posts 10, as shown in Fig. 2. The rubber sheets 17 are provided at the corner juncture of the legs 18 and 19 with a solid integral rubber bead portion 20 to give the sheet rigidity. The rubber lengths 17 may be provided to cover two or more of the posts 10, but preferably are just slightly longer than the distance between two posts. They can then be positioned with their ends in overlapping relationship in the direc-

tion of the running of the horses (counterclockwise in the United States). This will prevent the horse from rubbing against the rail and engag-
ing the overlapping edge of the length of rubber sheeting 17.

To fasten the guard rail sheets 17 to the posts and to provide them with additional rigidity, I prefer to interlace each sheet 17 with lengths of rubber covered wire 21, as shown in Figs. 1 and 3. The upper portion 18 of each sheet may be interlaced with two spaced rows of wires 21, and the short vertical portion may be interlaced with one row of wires 21. By using a stiff rubber covered wire, the rubber sheeting 17 may be given rigidity in addition to the bead portion 20 along the comparatively thin portions 17 and 19. At the termination of each length of sheeting 17, the wire may be wrapped around the adjacent portion of the post as shown in Fig. 2. It is preferable that the wire be not tied to the posts but merely given a sufficient number of turns, three shown, to hold the sheets 17 rigidly to the posts, but to permit a release of the section of rail under the impact of a plunging horse.

With the above construction, it is evident that I have provided a guard rail which is sufficiently rigid for the purposes required and which will give the jockey an adequate view of the rail from a speeding horse. The width of the upper portion for this purpose may be approximately six inches. The turned fastenings of the wire to the posts 10 are made strong enough to withstand the accidental bumping which often takes place in a race. If a horse should be bumped sidewise into the rail, it will give slightly and enable the horse to right itself without injury to the horse or rider. In view of the smooth surface of the rubber, the horse will not pick up splinters nor tear its skin in any manner. Should a horse bolt and plunge directly into the guard rail, the wires 21 will unwind under the impact of the horse and the section of guard rail will give way. The horse may stumble and even fall, but he will not break any bones nor suffer any injury by virtue of his hitting a solid wooden rail. Occasionally a horse will even try to jump over a rail and be seriously injured thereby. It is quite obvious that the rail of the present invention will collapse under the weight of the horse before the horse is injured.

If desired, the posts 10 may be placed into removable sockets or even in collapsible sockets, so that the posts themselves will give way under the weight of the horse.

While I have described a specific embodiment of my invention, it is obvious that changes may be made in the size, shape and relative arrangement of parts without departing from the spirit and scope of the invention as defined in the appended claims.

I claim:

1. A guard rail comprising a plurality of spaced posts, each of said posts having the top end thereof formed into a generally rectangular loop extending laterally from said post, and a resilient sheet rubber rail having an L-shaped cross-section extending between said posts, one leg of said L-shape extending horizontally across the top of said loop portion and the vertical leg extending along the outer vertical edge of said loop.

2. A guard rail comprising a plurality of spaced posts, each of said posts having the top end thereof formed into a generally rectangular loop extending laterally from said post, and a resilient sheet rubber rail having an L-shaped cross-section extending between said posts, one

leg of said L-shape extending horizontally across the top of said loop portion and the vertical leg extending along the outer vertical edge of said loop, the corner edge of said rail having an integral stiffening bead.

3. A guard rail comprising a plurality of spaced posts, each of said posts having an integral generally rectangular portion extending laterally adjacent the top end thereof, and a resilient rail having an L-shaped cross-section extending between said posts, one leg of said L-shape extending horizontally across the top of said rectangular portions and the vertical leg extending along the outer vertical edge of said rectangular portions, said resilient rail having a plurality of wires interlaced longitudinally thereof, said wires being fastened to said posts.

4. A guard rail comprising a plurality of spaced posts, each of said posts having the top end thereof formed into a generally rectangular loop extending laterally from said post, and a resilient sheet rubber rail having an L-shaped cross-section extending between said posts, one leg of said L-shape extending horizontally across the top of said loop portion and the vertical leg extending along the outer vertical edge of said loop, said resilient rail having a plurality of wires interlaced longitudinally thereof, said wires being fastened to said posts.

5. A guard rail comprising a plurality of spaced posts, each of said posts having the top end thereof formed into a generally rectangular loop extending laterally from said post, and a resilient sheet rubber rail having an L-shaped cross-section extending between said posts, one leg of said L-shape extending horizontally across the top of said loop portion and the vertical leg extending along the outer vertical edge of said loop, the corner edge of said rail having an integral stiffening bead, said resilient rail having a plurality of wires interlaced longitudinally thereof, said wires being fastened to said posts.

6. A guard rail comprising a plurality of spaced posts, each of said posts having an integral generally rectangular portion extending laterally adjacent the top end thereof, and a resilient rail having an L-shaped cross-section extending between said posts, one leg of said L-shape extending horizontally across the top of said rectangular portions and the vertical leg extending along the outer vertical edge of said rectangular portions, said resilient rail having a plurality of wires interlaced longitudinally thereof, said wires being fastened to said posts to retain said rail on said posts under normal pressure but to release from said posts under a sudden heavy impact.

7. A guard rail comprising a plurality of spaced posts, each of said posts having the top end thereof formed into a generally rectangular loop extending laterally from said post, and a resilient sheet rubber rail having an L-shaped cross-section extending between said posts, one leg of said L-shape extending horizontally across the top of said loop portion and the vertical leg extending along the outer vertical edge of said loop, said resilient rail having a plurality of wires interlaced longitudinally thereof, said wires being fastened to said posts to retain said rail on said posts under normal pressure but to release from said posts under a sudden heavy impact.

8. A guard rail comprising a plurality of spaced posts, each of said posts having the top end thereof formed into a generally rectangular loop extending laterally from said post, and a resilient

sheet rubber rail having an L-shaped cross-section extending between said posts, one leg of said L-shape extending horizontally across the top of said loop portion and the vertical leg extending along the outer vertical edge of said loop, the corner edge of said rail having an integral stiffening bead, said resilient rail having a plurality of wires interlaced longitudinally thereof, said wires being fastened to said posts to retain said rail on said posts under normal pressure but to release from said posts under a sudden heavy impact.
